UNITED STATES PATENT OFFICE.

JOHN T. HUME, OF CHICAGO HEIGHTS, ILLINOIS, ASSIGNOR TO CHICAGO PNEUMATIC TOOL CO., OF CHICAGO, ILLINOIS.

SPEED-CONTROLLING APPARATUS.

1,081,832.

Specification of Letters Patent. Patented Dec. 16, 1913.

Application filed December 14, 1911. Serial No. 665,753.

To all whom it may concern:

Be it known that I, JOHN T. HUME, a citizen of the United States, residing at Chicago Heights, in the county of Cook and State of Illinois, have invented a certain new and useful Improvement in Speed-Controlling Apparatus, of which the following is a full, clear, concise, and exact description, reference being had to the accompanying drawings, forming a part of this specification.

My invention relates to controlling devices and more particularly to speed controlling devices and has for its object the provision of an improved device which may be attached to any suitable prime mover to control its operation.

In the preferred form of the invention which is the form illustrated herein, the device is applicable particularly in connection with explosive engines and when the device is so applied it provides suitable controlling facilities which may prevent operation of said explosive engine beyond a certain definite speed. In the form herein shown the device is self-contained and has suitable circuit controlling devices, which circuit controlling devices are automatically operated upon and controlled by a governor.

The form of the invention which is illustrated herein has suitable governing appliances responsive to changes in speed and these governing devices preferably carry the spark controlling elements of the explosive engine. When the device is desired to prevent operation beyond a certain predetermined speed limit, then the governing appliances are so arranged that should the speed exceed a given predetermined amount, the device prevents the establishment of the necessary conditions whereby an explosion is occasioned. When the speed is reduced to normal the device again permits the explosions to take place in the normal way.

In describing the specific form of the invention herein both in what has preceded and in the specific description that will follow, it is not meant to limit the invention to this particular form as the invention is capable of wide variation and use and in a variety of different ways. I will however describe specifically a form of carrying out the invention in connection with the accom-

panying drawings illustrating said form, in which:

Figure 1 is a plan view of the device with the cover removed illustrating various parts; Fig. 2 is a similar view showing the device in its normal operating condition; Fig. 3 is a similar view showing the device in an alternate condition; Fig. 4 is a central view of the movable elements of the device viewed from the opposite side illustrated in Figs. 1, 2 and 3; Fig. 5 is a sectional view on line a—a of Fig. 2, and Fig. 6 is a diagram of the circuit arrangements.

Referring more particularly to Fig. 6, in order to describe the general operation of the device I set forth two spark plugs 1, 1, respectively associated with secondary windings 2, 2, which secondary windings are in inductive relation with primary windings 3, 3. A battery 4 grounded at 5 furnishes the necessary current and the spark plugs are suitably grounded at 6, 6, the ground representing preferably the frame of the gas engine with which the device is associated. The circuit through the primary windings is controlled by contact rollers 7, 7 which are preferably insulated from the cup shaped casing 8 of the device, and contact is established between the frame of the machine 9 and the rollers 7, 7 through the agency of a roller 10 rotatably mounted about a shaft 11. Suitable governing devices to be explained hereinafter permit engagement between the roller 10 and the rollers 7, 7 as the shaft 11 is being rotated, but prevent contact between the elements 10 and 7 should the speed of the shaft 11 exceed a predetermined amount. Thus if the engine is running at a speed below a predetermined amount, then the roller 10 normally engages the rollers 7, 7 to permit sparking conditions to be established at the spark plugs 1, 1, but when the speed exceeds a predetermined amount, the roller 10 as it is carried about the shaft 11 fails to engage the rollers 7 and thus the engine misses an explosion or more if necessary until the speed of the engine is reduced to the proper predetermined amount. This will serve to explain the general features of the device and the specific construction will now be set forth in connection with the remaining views.

The device itself consists of a cylindrical

casing 8 which has at one side a bearing 9 for the shaft 11 and which casing is provided with a cap 12 screw threadedly associated with the casing 8 which also carries 5 a bearing 13 to accommodate the shaft 11. Two contact rollers 7, 7 are rotatably mounted about the stems 14, 14 and these stems are held in place within the casing by means of nuts 15, 15. Suitable insulation 16, 16 10 and 17, 17 is provided so that the elements 14 and 7 are not electrically associated with the casing 8. The rollers may rotate about their respective stems. It may be said further that the roller 10 previously referred 15 to is electrically connected with the casing 8 as will appear and this casing 8 is grounded at 9 (Fig. 6), the ground again preferably being the framework of the explosive engine. The roller 10 which periodically 20 engages the rollers 7, 7 to make contact therewith is rotatably mounted upon a stem 18 carried by an element 19. A second element 20 similar in form to the element 19 but oppositely disposed is provided with a slot 25 21 through which the stem 18 projects so as to permit play between the elements 19 and 20. The elements 19 and 20 are respectively rotatably mounted upon a V shaped arm 22 by means of pins or bolts 23. 30 The V shaped arm 22 is fixedly secured to the shaft 11 and thus as the shaft rotates the elements 10, 19, 20 and 22 are carried around with the said shaft. The great bulk of the weight of the elements 19 and 20 is at their 35 free extremities as is apparent and the faster the shaft rotates the farther these elements 19 and 20 at their free extremities tend to separate by reason of the centrifugal force. The greater the separation between the elements 19 and 20 at their free extremities, the 40 farther is the roller 10 carried radially toward the axis of the shaft 11 and when the separation has reached a predetermined amount the roller 10 in its rotation fails to 45 engage the rollers 7, 7, under which conditions the engine misses its explosion. A spring 24 fastened between pins 25 and 26 tends to hold the elements 19 and 20 together and the strength of this spring controls 50 said elements 19 and 20 so that the proper separation due to centrifugal force may occur at the proper time. An additional pin 27 is provided so that the spring 24 may be placed under additional tension 55 so as to change the speed limit at which the device is operative to withhold sparking conditions. It will thus be seen that the device acts as a combined circuit controller and governor, and as such may be used in a variety 60 of different ways and under different though equivalent conditions.

Having thus described one form which my invention may take, which form is not in-

tended to limit the broad features of the invention thereto, what I claim as new and desire to secure by Letters Patent is:

1. A device of the character described having a circuit controlling element, a second circuit controlling element adapted for periodic engagement with said first aforesaid circuit controlling element, a shaft, an arm fixedly secured to said shaft, and a governor pivoted on said arm and carrying said second circuit controlling element having means to move said second circuit controlling element radially in response to the movement of said governor.

2. A device of the character described having a circuit controlling element, a second circuit controlling element adapted for periodic engagement with said first aforesaid circuit controlling element, a shaft, an arm fixedly secured to said shaft, and a governor pivoted on said arm and carrying said second circuit controlling element having means to move said second circuit controlling element radially in response to the movement of said governor.

3. A device of the character described comprising a shaft, a stationary framework associated therewith, a circuit controlling element mounted upon said framework, an arm carried by said shaft, a centrifugal governor pivotedly mounted on said arm, and a second circuit controlling element carried by said governor movable radially with respect to said shaft in response to the movements of said governor.

4. A device of the character described having a shaft, a stationary framework, a circuit controlling element carried by said framework, a pair of radial arms carried by said shaft, a pair of symmetrically arranged centrifugal governor elements pivotedly mounted respectively upon said arms, and a second circuit controlling element carried by one of said governor elements.

5. A device of the character described having a shaft, a stationary framework, a circuit controlling element carried by said framework, a pair of radial arms carried by said shaft, a pair of symmetrically arranged centrifugal governor elements pivotedly mounted respectively upon said arms, a second circuit controlling element carried by one of said governor elements, and resilient means associated with said governor elements tending to hold them in their retracted position.

In witness whereof, I hereunto subscribe my name this first day of December, A. D., 1911.

JOHN T. HUME.
